UNITED STATES PATENT OFFICE.

EDWARD HARDY, OF COLCHESTER, ILLINOIS.

AMUSEMENT DEVICE.

Application filed January 4, 1922. Serial No. 526,882.

To all whom it may concern:

Be it known that I, EDWARD HARDY, a citizen of the United States, and a resident of Colchester, in the county of McDonough 5 and State of Illinois, have invented certain new and useful Improvements in Amusement Devices, of which the following is a specification.

This invention relates to an amusement 10 device and more particularly to a combined teeter and swing.

Among the objects of the present invention is to provide a device of the above character which may be operated with safety by 15 children and which is durable and inexpensive to manufacture.

Other objects and objects relating to details of construction, combination and arrangement of parts will hereinafter appear 20 in the detailed description to follow.

The invention is illustrated by way of example in the accompanying drawings, in which the figure is an enlarged perspective view illustrating the invention.

25 Referring more particularly to the drawings, A indicates generally a post or support, B a rocker or teeter beam and C a pair of swing frames, one being secured on each end of the beam B.

30 The beam B comprises a pair of studding 10 which have secured between their similar ends in each instance a bar 11 by the means of bolts as indicated at 12. Upon the upper end of the post A there is pivoted a short 35 bar member 13 by the means of the screw or bolt indicated at 14 and said bar 13 having its ends connected to the two beam members 10 through the means of chains as indicated at 15. The chains are adapted to permit 40 free rocking movement of the beam B and the bar 13 adapted to permit said beam to turn or rotate about the post A.

45 Adjacent the upper end of the post A there is formed a pair of opposing collars 16 which are preferably of the shape shown and spaced from each other. Between the collars 16 there is interposed an annular member freely turnable about the post A and formed with a pair of diametrically opposed 50 ears 17. To each ear 17 there is connected a rope or cable 18 which has its other end connected with a rung 19 which extends between the beam members 10 on the associated side of the beam.

55 To each bar 11 there is secured a cross

member and support 20 by a bolt 32. Each cross member carries a pair of hooks 21, one at each end thereof, which are adapted to pivotally suspend the frames C. Each frame C comprises the two vertical members 60 22 which carry at their upper ends the staples or eyes 23 adapted to connect with the hooks 21. The lower ends of these members in each instance are connected by a cross member 24 which supports a seat 25, and 65 above the seat there is secured a loop 26, said loop being connected between the vertical members 22 and secured by the means of staples or the like as indicated at 27. Also it may be pointed out that the bars 70 are each provided with a plurality of holes as at 28, in order that the bars 20 may be positioned near the pivotal center of the beam B if so desired.

Immediately below each of the swing 75 frames C there is positioned an approach or ladder generally indicated by the reference numeral 29. As is seen the approach 29 consists in a ladder 30 which is properly braced and supporting a platform 31 at its 80 upper end.

In the operation of the present device a juvenile may assume the seating position in each of the frames C. This may be done by ascending the approachers 29. If it is desired to swing then each occupant of the swing frames may sway their body so that a swinging motion of the frame will be produced. If the swinging of each frame is in synchronism then no teetering action of 85 the beam B will be had. If however the frames C are swung in opposite directions by the occupants then the beam B will become unbalanced and a teetering action will 90 occur with the swinging. The cables 18 will 95 of course limit the amount which the beam B may swing. Also as is obvious if desired the occupants may maneuver to turn or rotate the beam B and thus increase their amusement.

100 I claim:—

1. An amusement device of the character described, comprising a support, a beam pivoted at a point intermediate its ends upon said support and adapted for vertical 105 rocking movement, a cross member at each end of the beam, a frame carried by each cross member adapted for transverse swinging movement with relation to the beam, and a hoop supported within each frame and 110

adapted for permitting the weight of the person seated within a frame to be shifted to cause rocking movement of the beam.

2. In combination, a vertical post, a beam comprising a pair of elongated members secured together at adjacent ends and connected to said vertical post for swinging movement at the longitudinal center, a cross member carried at each end of the beam, a 10 U-shaped frame member having its ends pivotally connected to the ends of each of said cross members and adapted for transverse swinging movement with relation to the beam, a seat carried by the bridge portion of each U-shaped frame, and a hoop positioned above said seat in each frame and secured to the leg members of said frame.
3. In a device of the character described, a post, a beam consisting of a pair of elongated members secured to each other in spaced relation and having a longitudinally adjustable extension at each end disposed between the members, means whereby the elongated members may be supported by 20 said posts at a point intermediate its ends for vertical swinging movement, a cross bar

carried at the outer end of each of said extensions, and a swing frame carried by said cross member and adapted for transverse swinging movement with relation to the associated extension. 30

4. An amusement device of the character described comprising a support, a beam pivoted at a point central to its length upon said support and adapted for vertical rocking movement, a cross member carried at each end of the beam, means whereby each cross member may be adjustably moved inwardly or outwardly with respect to the support for said beam, a frame pivotally supported by each cross member and adapted for inward and outward swinging movement with respect to the beam support, each frame including a pair of side members having their upper ends pivotally connected to the associated cross support, and a seat supported between the side members of each frame. 35 40 45

EDWARD HARDY.
